UNITED STATES PATENT OFFICE.

FREDERICK J. KALDENBERG, OF NEW YORK, N. Y.

DESIGN FOR A BRUSH-HANDLE.

SPECIFICATION forming part of Design No. 16,190, dated August 4, 1885.

Application filed October 25, 1883. Term of patent 7 years.

To all whom it may concern:

Be it known that I, FREDERICK J. KALDENBERG, a citizen of the United States, residing at New York, in the county and State of New 5 York, have invented and produced a new and original Design for Handles of Brushes, of which the following is a specification, reference being had to the accompanying drawings, forming part thereof.

10 Figure 1 is a side elevation of my new design for a handle, and Fig. 2 is an end view of the same.

This invention is intended to provide a novel and ornamental design for the handles of 15 brushes, toilet-mirrors, cutlery, and other articles; and the leading feature of my design consists in a longitudinally ribbed or beaded surface, as will be fully hereinafter set forth.

In the drawings, *a* represents the handle of 20 a brush, slightly tapering, and of the usual

flat shape. *b b* are ribs or beads extending longitudinally along the handle, presenting, when viewed in end section, (see Fig. 2,) a scalloped outline or periphery. At the upper or outer end of the handle these ribs converge and are 25 lost in a single line or point, as shown at *c*. The entire surface of the handle may be provided with these convex ribs, producing an unbroken indented outline on its outer surface.

I claim as my invention—

30 The design for a brush-handle, consisting of a handle having a ribbed surface of an approximately oval shape in cross-section, the ribs converging at the outer end of the handle, as shown and described.

FRED. J. KALDENBERG.
